UNITED STATES PATENT OFFICE.

AUGUSTUS B. FELGEMAKER, OF ERIE, PENNSYLVANIA.

REGISTER-STOP FOR PIPE-ORGANS.

SPECIFICATION forming part of Letters Patent No. 626,414, dated June 6, 1899.

Application filed August 27, 1898. Serial No. 689,652. (No model.)

To all whom it may concern:

Be it known that I, AUGUSTUS B. FELGEMAKER, a citizen of the United States, residing at Erie, in the county of Erie and State 5 of Pennsylvania, have invented certain new and useful Improvements in Register-Stops for Pipe-Organ; and I do hereby declare the following to be a full, clear, and exact description of the invention, such as will enable others skilled in the art to which it 10 pertains to make and use the same.

This invention relates to register-stops for pipe-organs; and it consists in certain improvements in the construction thereof, as 15 will be hereinafter fully described, and pointed out in the claims.

The invention is illustrated in the accompanying drawings as follows:

Figure 1 shows a plan view of the device; 20 Fig. 2, a section on line 2 2 in Fig. 1; Fig. 3, a sectional view of the stop-lever mechanism.

A marks an air-chamber from which the pipes B are supplied, the air passing from the air-chamber A through a port a, a valve A', 25 port a', and opening a². There is a chamber A for each register, and this chamber is in communication through ports—such as a, a', and a²—with all the pipes of the same register. Air under constant pressure is contained in a chamber C and is normally cut off from the air-chamber A by the valve c. When 30 the valve c is open, the air passes through the port C', chamber C², and port a³ to the chamber A. The valve c is carried by a stem c'. This stem is connected with the movable plate c² of a bellows-motor c³. The bellows-motor is connected by the ports C⁴ and C⁵ with the chamber C. Two valves d and d², carried by the stem d', operate at the ends of the port C⁵, the valve d closing the port C⁵ to the atmosphere and the valve d² controlling the port C⁵ at its entrance to the chamber C. These 35 valves d and d² are so arranged on the stems d' that when one of them is closed the other is open. The stem d' is connected with the movable plate d³ of a bellows-motor D. The duct D' leads from the bellows-motor D through a port e² to a chamber E. (See Fig. 3.) A valve e normally closes the port e², and 40 a spring e' assists the air-pressure in closing the valve e. A stop-lever F is connected by a stem e⁴ with the valve e. By moving the stop-lever F the valve e is opened and air which is maintained under pressure in the chamber E passes through the port e² and port 55 D' to the bellows-motor D. This raises the plate d³, carrying the stem d' and valves d and d² upwardly, so that the valve d² closes the port C⁵ at its entrance to the chamber C and the valve d opens the port C⁵ to the atmosphere. 60 The area of the movable plate c² of the bellows-motor c³ is somewhat larger than the area of the valve c, so that when the air-pressure is reduced in the bellows-motor c³ the air-pressure, being greater upon the greater area of the 65 bellows-motor, effects a movement of said motor and a consequent raising of the valve c and passage of air from the chamber C to the chamber A, where it is let into the pipes as each key is touched. The chamber C runs transversely 70 of the chambers A and contains air from which all the different registers are supplied. The number may be increased indefinitely. When the stop-lever F is moved back to its normal position, the valve e is closed. A 75 valve e⁵, carried by the stem e⁴, closes the passage e³ while the valve e is open. When the valve e is closed, this valve e⁵ opens the passage e³, which is in communication with the port e², to the atmosphere, thus reducing the 80 pressure in the duct D' and bellows-motor D. This reduction of pressure in the bellows-motor and the air-pressure in the chamber C effect a movement of the plate d³ of the bellows-motor D and a consequent closing of the 85 valve d and an opening of the valve d². This opening of the valve d² allows the air in the chamber C to pass through the ports C⁵ and C⁴ into the bellows-motor c³, where by reason of the greater area of the plate c² it is moved 90 downwardly, thus closing the valve c and cutting off the air-supply from the chamber A. A passage c⁴ leads from the chamber C² to the atmosphere, and a valve c⁵, carried by the stem c', opens this passage when the valve c is closed 95 and closes it when the valve c is open. The result of this is that when the valve c is closed, and thus cuts off the air from the chamber A, the air in the chamber A is immediately reduced to atmospheric pressure through the 100 opening c⁴, so that when keys are operated to effect tones from other registers the air in the registers cut out is so reduced as to prevent the pipes of that register speaking.

This construction is simple, allows an indefinite multiplication of the registers in a very compact manner, and operates quickly and effectively.

5 What I claim as new is—

1. In a register-stop, the combination with the air-chamber leading to the pipes; of the chamber, C, in communication with said air-chamber; the valve, c, controlling said communication; a primary motor as c³, operated by the air-pressure in the chamber, C, for controlling the valve, c; passages leading from said motor, c³, to the air-chamber, C, and to the atmosphere; valves controlling said passages; a secondary motor in the chamber C arranged to open and close said valves alternately, said motor being operated in one direction by air from the stop mechanism and in the opposite direction by the pressure of 20 the air in the chamber C on said motor; a passage leading from said motor; a valve for controlling said passage; and stop mechanism for operating said valve.
2. In a register-stop, the combination with 25 the chamber A, from which air is supplied to the pipes; of the air-chamber C, communicat-

ing with the chamber A, through the passage, C' C² and a³; valve, c, controlling said passage; a stem, c', carrying said valve; passage, c⁴, from the passage, C², to the atmosphere; 30 valve, c⁵, carried by the stem, c', and controlling the passage, c⁴; the bellows-motor, c³, having its movable part connected with the stem, c'; duct, C⁴, and port, C⁵, leading from said motor, C³, to the atmosphere and to the 35 chamber, C; valve, d, controlling the entrance of the port, C⁵, to the atmosphere; valve, d², controlling the entrance of the port, C⁵, to the chamber, C; bellows-motor, D, arranged in the chamber C and having the movable part, d³, connected with the stem, d'; the air-duct, D', leading to the motor, d³; an air-supply in communication with the duct, D'; a valve controlling said air-supply; and a stop-lever controlling said valve. 40

In testimony whereof I affix my signature in presence of two witnesses.

AUGUSTUS B. FELGEMAKER.
